UNITED STATES PATENT OFFICE.

JOHN H. PILLINGS, OF HAMILTON, OHIO, ASSIGNOR TO THE NATIONAL AUTOMATIC TYPEWRITER COMPANY, OF HAMILTON, OHIO, A CORPORATION OF OHIO.

MECHANISM FOR OPERATING TYPE-WRITING MACHINES.

1,174,090.

Specification of Letters Patent.

Patented Mar. 7, 1916.

Application filed May 15, 1915. Serial No. 28,323.

To all whom it may concern:

Be it known that I, JOHN H. PILLINGS, a citizen of the United States, residing at Hamilton, in the county of Butler and State 5 of Ohio, have invented a certain new and useful Improvement in Mechanism for Operating Type-Writing Machines, of which the following is a full, clear, and exact description.

10 In the McCall Patent No. 1,024,092, certain mechanism is shown and described which include a series of levers and means whereby they may be selectively rocked in such sequence as is determined by the perforations in a controller strip. The mechanism as shown in said patent was especially designed for use with a typewriting machine as the means for automatically operating the key levers and various other parts 15 thereof, to which the levers of the mechanism shown in said patent were to be connected.

The present invention relates to improvements in the mechanism of said prior patent, the objects being to render said mechanism more efficient and less liable to injury, more readily assembled or disassembled, wholly or partly, for purposes of repair, and more easily connectible with the 20 typewriting machine in such wise that while it will automatically operate the typewriting machine it will not interfere with the ordinary manual operation of said typewriting machine when that is desired.

25 The invention consists in the construction and combination of parts shown in the drawings and hereinafter described and pointed out definitely in the appended claims.

30 In the drawings, Figure 1 is a vertical sectional view in a plane extending from the front to the rear end of the machine; Fig. 2 is a top plan view of the rear end of one of the levers D; Fig. 3 is a sectional view 35 rear elevation in the plane indicated by line 3—3 on Fig. 1. A very considerable part of the machine between the two sides thereof is broken out of this Fig. 3. Fig. 4 is a side view of one of the links by which 40 the levers D are connected with the levers of a typewriting machine; Fig. 5 is a front view of one of the same links; Fig. 6 is a side elevation partly broken away of certain parts of one of the said links, and Fig. 45

7 is a sectional plan view of the part shown 55 in Fig. 6.

The frame work F, by which the various movable parts of the present invention are supported, is so constructed that an ordinary typewriter, of which a portion T is 60 shown in Fig. 1, may be secured thereon with its parts, such as key levers L, etc., in the proper position for connection with the mechanically operated levers of the present invention.

55 The typewriter operating mechanism is generically like that which is shown in said prior patent. It includes a cylinder A rotatably mounted at the rear end of the machine and extending transversely and having in its surface a large number of longitudinal grooves a. A perforated controller strip B runs over and moves with this cylinder. A plurality of parallel levers D are fulcrumed on fulcrum bar I so that they 70 may be displaced endwise slightly and rocked when so displaced. A vertical pin H is movably mounted in the rear end of each lever, and this pin rides on the surface of the controller strip B as it passes 75 over the cylinder A, but will drop through any perforation in said strip which passes under it, and into one of the grooves a whereby, as the cylinder turns in the direction shown by the arrow on Fig. 1, said 80 lever will move endwise forward. This carries a specially formed part of said lever into the path of a part carried by a vertically reciprocating bar K, by which the displaced lever is rocked; and after this said 85 lever is automatically returned to its initial position. The said cylinder and controller strip, and the means for turning the cylinder may be like the corresponding parts as shown in said prior patent; but in all other 90 respects the mechanism shown in the drawing and now to be described is specifically unlike the corresponding parts as shown in said prior patent.

95 The levers D are all alike. Each has at 100 its rear end a plurality of vertically perforated ears d, in which the pin H is movably mounted. Each pin H has a shoulder h which lies above the lower ear, and thereby prevents said pin from dropping out. 105 A spring h' engages the upper end of said pin, and acts to move it down. As shown this spring is made of fine wire which is at-

2
tached to the side of the lever, and is carried from its point of attachment over the top of said lever rearward between two little ears b' formed on the lever, and then 5 upward and downward in the form of an inverted U-loop, and thence into the perforation of the upper ear d and against the upper end of the pin H . Each lever D has a horizontal elongated slot d^4 through it 10 for the reception of the fulcrum bar I ; and from this slot a narrower slot d^5 extends downward and forward to the lower edge of said bar.

Near the front end of the machine is a 15 fixed comb J ; and near the rear end of the machine is another fixed comb J' . Each of these is a vertical transversely extended thin metal bar having a plurality of properly placed slots j therein extending from its top 20 edge downward. Each lever D at its front end passes through one of the slots of the comb J ; and adjacent to its rear end passes through one of the slots in the comb J' . In this manner the parallelism of the levers D 25 is preserved, and said levers are prevented from moving laterally upon their fulcrum bar I . This fulcrum bar is a cylindrical bar in which and between each pair of levers inclined notches i and i' are cut, thereby reducing the notched parts of the bar to the 30 form of a flat inclined bar (as shown in Fig. 1), which is a trifle narrower than the slot d^5 and extends in substantially the same direction. This fulcrum bar I is supported at 35 its ends in frame members F^2 in which it may move endwise under certain conditions. In its surface is an elongated slot into which projects a screw which screws down through one of said supporting frame members. By 40 means of this screw this fulcrum bar may be set in the required position such that the levers D are supported upon the cylindrical parts thereof. But if one loosens this set screw however, this fulcrum bar may be 45 moved endwise far enough to bring the notched parts thereof within the levers, that is to say, into registering relation with the slots d^5 . The upper edges of the narrowed parts of the fulcrum bar which now lie 50 within the levers will support the levers so that they will not drop. If, now, it is desired to remove one of the levers one has only to lift it upward and rearward slightly, and its slot d^5 will pass over the narrowed 55 or flattened part of the fulcrum bar.

On the lower edge of each lever D is a thickened boss d^6 having a forwardly extended shoulder d^7 and a downwardly extended spur d^8 whose rear face is beveled. 60 Beneath all of these levers is a transversely extended bar K which is fixed at its ends to the rear ends of two rocking levers k^2 which are fulcrumed on a transversely extended shaft M . A constantly rotating 65 shaft N which is mounted in the side frame

members carries two eccentrics n . Eccentric straps P engage these two eccentrics; and each is provided with an upwardly extended arm p , which is pivotally connected with one of the rocking levers k^2 . 70 From this it will be evident that while the machine is in operation this bar K will be reciprocating vertically up and down. This bar carries a plurality of pivoted pawls k , each of which is placed in the same vertical 75 forwardly extended plane as that in which the associated lever D lies. Each of these pawls is normally under the influence of a spring k' acting to yieldingly hold it in the operative position shown in Fig. 1. The 80 upper rear ends of the pawls k will not, as the bar K is moved up and down, touch any of the levers D which are in the normal position, but when one of said levers has been displaced forward as previously explained, it will bring the lug d^6 into the path of the associated pawl k . When the bar K makes its next upward trip, the corresponding pawl k will engage the lug d^6 of the displaced lever. However little the 85 lever has been displaced this pawl will engage the bevel rear face of the spur d^8 , and therefore the continued engagement of the pawl with the lever is insured until the lever has been rocked, as it will be by the 90 upward movement of said bar K . If, by chance, the bar K is up when one of these levers D is displaced, the rear face d^7 of the lug d^6 will engage the rear face of the corresponding pawl k , and will cause it to rock 95 forward on its pivotal support, and therefore no damage will be done to the mechanism.

After each lever has been rocked as stated, it is moved rearward to its normal 100 position by a spring U' . There is one of these springs for each lever D . These are bent flat springs, and they are all secured to a transversely extended bar V which is fixed to two arms f of the frame work of 105 the machine. Close to the front end of each lever D is a vertical slot d^9 which extends 110 from its lower edge upward.

Each of the levers D has its front end 115 connected with a vertically movable member of the typewriter, as, for example, one of the key levers L , by a substantially vertical link E . This link includes two members capable of sliding up and down relatively to one another, and a spring e^3 by which the lower 120 link member is yieldingly supported by the upper member. The lower member comprises two parallel narrow flat bars e , and an integral top bar e' , which connects their upper ends. The lower ends of these side 125 bars e are connected by a horizontal pin e^2 . The front end of the associated lever D passes between these two side bars e , and the pin e^2 enters the vertical slot d^9 in said lever D . The upper link member comprises 130

a rod e^4 whose upper end is pivotally connected with the overlying movable member L; a vertically grooved slide e^5 which is located between the two side bars and is screwed onto the threaded lower end of the rod e^4 . The spring e^3 is a relatively long coiled spring which surrounds the rod e^4 and engages at its upper end with the top bar e' , while its lower end lies in a recess e^7 in the slide and engages with said slide. This spring yieldingly upholds the lower link member in such position that normally the pin e^2 lies well toward the top of the slot d'' . When the lever D is rocked this spring acts as a shock absorber to prevent any jerk on the lever L, and to impart to it a movement which is much like that which it has when depressed manually. When desired, the typewriter keys may be actuated manually without causing any movement of any part of the described operating mechanism except that the upper member of the associated link will move down with lever L, and this will be accompanied by a slight downward movement of the lower link member, which movement however will not be great enough to carry the pin e^2 to the lower end of the slot d'' . When one wishes to adjust the effective length of any link the lower link member will be drawn down far enough to withdraw the pin e^2 from slot d'' ; then the lower end of the link may be swung forward, and this will permit the lower link member to be turned, and this will cause the slide e^5 to travel up or down on the rod e^4 .

Having described my invention, I claim:

1. In mechanism of the character described, the combination of a plurality of parallel levers each having a longitudinally elongated slot, and a narrower outlet slot which extends from said elongated slot to the lower edge of said lever, two combs which respectively engage said levers near their front and rear ends and thereby prevent any substantial lateral movement of said levers, a fulcrum bar which passes through all of said elongated slots, said fulcrum bar being formed with alternately disposed parts which can not pass through said elongated outlet slots and intermediate disposed narrow parts which may pass through said outlet slots, supports in which said fulcrum bar is slidably mounted, and means to prevent the endwise sliding movement of said fulcrum bar and to hold it in such position that its narrow parts lie between the levers.

2. In mechanism of the character described, the combination with a longitudinally grooved cylinder and a perforated controller strip running over the same, of a plurality of levers each having a longitudinally elongated slot, a horizontal fulcrum bar which goes through said slots and

pivotally supports said levers, a pin vertically movable in the rear end of each lever and projecting below the same into contact with said controller strip, a spring engaging the upper end of each pin and pressing it downward, means limiting the downward movement of the said pin, and means for rocking any of said levers which has been displaced endwise by the action of the cylinder on any pin which has passed through a perforation in said strip and into one of the longitudinal grooves in the cylinder.

3. In mechanism of the character specified, the combination of a plurality of longitudinally displaceable levers each having a longitudinally elongated slot, a horizontal fulcrum bar, which goes through said slots and supports said levers, means for displacing said levers endwise in predetermined sequence, a vertically reciprocating transversely extended horizontal bar, a plurality of pawls pivoted on said bar and severally adapted to engage and rock the levers which are displaced endwise, and means for returning said levers to their initial positions after they have been rocked as stated.

4. In mechanism of the character specified, the combination of a vertically reciprocating transversely extending horizontal bar, a plurality of pawls pivoted thereto and projecting upward therefrom, a plurality of endwise displaceable levers which lie respectively over said pawls,—each of said levers having a pawl engaging surface which normally lies out of the path of the associated pawl but which is carried into said path by the endwise displacement of said lever, and said lever having also a vertical shoulder which lies just in front of said pawl engaging surface and just behind the path in which the upper end of the associated pawl travels.

5. In mechanism of the character specified, the combination of a vertically reciprocating transversely extending horizontal bar, a plurality of pawls pivoted thereto and projecting upward therefrom, a plurality of endwise displaceable levers which lie respectively over said pawls,—each of said levers having a pawl engaging surface which normally lies out of the path of the associated pawl but which is carried into said path by the endwise displacement of said lever, and a downwardly extended beveled spur adjacent to the front edge of said pawl engaging surface.

6. In mechanism of the character described, the combination of a plurality of longitudinally displaceable parallel levers each having an elongated slot and a horizontal fulcrum bar which goes through said slots and supports said levers, means for displacing said levers endwise in predetermined sequence, means for rocking each lever as displaced, and a cross bar extending trans-

versely over all of said levers, and a plurality of independent springs secured to said cross bar and each of said levers having a shoulder with the front face of which one 5 of said springs engage.

7. In mechanism of the character described, the combination of a pivoted lever capable of endwise displacement and having adjacent to its front end a vertical slot, 10 means for displacing said lever endwise and for rocking it when so displaced, an overlying vertically movable member, a link having a pivotal connection at its upper end with said overlying movable member and 15 having near its lower end a transverse pin which lies in the vertical slot in the first mentioned lever,—said link being composed of upper and lower members which are slideable vertically relative to one another, and a 20 spring by which the lower member is yieldingly supported from the upper member.

8. In mechanism of the character described, the combination of a pivoted lever having adjacent to its front end a vertical 25 slot, an overlying vertically movable member, and a link composed of two members, viz., a lower member comprising two parallel straps whose upper ends are connected by a cross bar, a pin extending between and 30 connecting the lower ends of said straps and lying in the vertical slot of the first mentioned lever, and an upper member comprising a rod which is pivotally connected with the overlying movable member and which

extends loosely down through the cross bar 35 of the lower link member, and a slide which is slideable vertically between the side bars of the lower link member, and has an adjustable connection with said rod, and a spring around said rod and between said slide and 40 cross bar.

9. In mechanism of the character described, the combination of a pivoted lever having adjacent to its front end a vertical slot, an overlying vertically movable member, 45 and a link composed of two members, viz., a lower member comprising two parallel straps whose upper ends are connected by a cross bar, a pin extending between and connecting the lower ends of said straps and 50 lying in the vertical slot of the first mentioned lever, and an upper member comprising a rod which is pivotally connected with the overlying movable member and which extends loosely down through the cross bar 55 of the lower link member, and a slide which is slideable vertically between the side bars of the lower link member, a nut lying between said side bars and below said slide and which is screwed onto the lower end of said 60 rod and a spring surrounding said rod and lying between said slide and cross bar.

In testimony whereof, I hereunto affix my signature in the presence of two witnesses.

JOHN H. PILLINGS.
